UNITED STATES PATENT OFFICE.

JESSE R. POWELL, OF CHICAGO, ILLINOIS, ASSIGNOR TO ARMOUR AND COMPANY, OF CHICAGO, ILLINOIS, A CORPORATION OF ILLINOIS.

TOILET ARTICLE.

Application filed May 16, 1921. Serial No. 470,068.

To all whom it may concern:

Be it known that I, JESSE R. POWELL, a citizen of the United States, residing at Chicago, in the county of Cook and State of Illinois, have invented certain new and useful Improvements in a Toilet Article, of which the following is a specification.

This invention has to do specifically with the production of a friable cosmetic cake 10 of toilet powder such as rouge or the like assembled with and supported by a disk or plaque and contained within a toilet case.

The invention has for its particular object the provision of such a supporting 15 plaque possessing characteristics which are conducive to the forming and maintaining of an intimate co-hesive bond between the plaque and the cake.

Such friable cakes of powder have been 20 heretofore mounted on plaques of glass and of metal and other fragile and vibrant substances. It is found, however, that in use a sudden jar as produced by the falling of the article on the dressing table or to the 25 floor or even by rough handling of the toilet case frequently causes a separation of the cake from its base, thus completely destroying the usefulness of the article.

This tendency to separation I have found 30 to be induced in a large degree by the inherent resilient or vibratory nature of the plaque under shock, and I propose to remedy the difficulty by providing a plaque mounting possessing a minimum of resiliency and 35 have adapted the same for an intimate union with the cosmetic cake.

In the accompanying drawings employed 40 to illustrate the manner of use of my invention—

Fig. 1 is a view in side elevation, showing a powder cake mounted upon the plaque of this invention;

Fig. 2 is a side elevation of a metal case within which is disposed the cake and 45 plaque; and

Fig. 3 is a vertical section through the metal case with lid removed, cake and plaque.

According to my invention I employ a 50 suitably shaped disk-like non-vitreous plaque 10 of inert material, possessing in a high degree non-fragile, non-resilient qualities, and I apply the cosmetic cake 11 thereto by a suitable adhesive or by pressing the

cake material into scarifications 12 formed 55 on the plaque surface.

The plaque may be formed appropriately by compressing into thin disks an inert, preferably fibrous, filler material such as wood pulp, asbestos or mixtures thereof combined 60 with a pitchy binder, preferably waterproof, such as phenol formaldehyde synthetic resins, asphalt, bitumen, or combinations thereof, etc. The resultant hard disk may be advantageously scarified to present a 65 roughened surface for the application of the cosmetic which will cause a most intimate adherence, and may also be treated with heat or otherwise as indicated to skilled workers in the art.

Plaques having cosmetic cakes mounted thereon are usually mounted in turn within a metal case 13 such as a brass box with hinged lid containing a small mirror. The plaque is usually attached to the bottom of 70 the box by glue, shellac or other hard cement. However the same conditions which promote the separation of the cake from the plaque also conduce to the separation of the plaque from the metal of the case; that is 75 80 to say the vibratory resilient qualities of the plaque and case under sudden jar disrupt the cement bond and the plaque and cake become loose within the box.

According to my invention I employ between the plaque and the bottom of the box a water-soluble or oil-soluble non-drying adhesive 14 of tenacious tacky character such as dextrin, glue or gum combined with 85 glycerin, calcium chloride or other similar 90 hygroscopic materials; or a resin combined with a non-volatile oil. Such an adhesive, remaining tacky, is not disrupted and the bond between it and the plaque and box persists despite rough usage even to the extent of momentarily shifting.

As a further provision to safeguard against accident I may interpose between the box bottom and the plaque a cushion pad of felt or the like which advantageously 100 is impregnated with my tacky adhesive, or the latter may be applied to the surfaces thereof.

It will thus be observed that I have produced a toilet article of the class described 105 which is practically proof against separation of the cake from its supporting plaque, and also of the mounted cake from the box

within which it is carried, even though the same be subjected to rough handling in distribution or accident in use.

I claim:

- 5 1. A toilet article comprising a cosmetic cake mounted upon a substantially non-resilient non-vitreous plaque of compacted inert filler and binder.
- 10 2. A toilet article comprising a cosmetic cake mounted upon a substantially non-resilient non-fragile plaque of compacted inert fibrous filler and waterproof binder.
- 15 3. A toilet article comprising a cosmetic cake mounted upon a substantially non-resilient non-vibrant plaque of compacted inert filler and a pitchy binder.
- 20 4. A toilet article comprising a cosmetic cake mounted upon a plaque of compacted inert filler and binder having a scarified contact surface.
- 25 5. A toilet article comprising a cosmetic cake mounted upon an inert plaque of compacted fibrous filler and pitchy binder, the plaque and attached cake secured within a

metallic case by means of a non-drying 25 tacky cement substance interposed between the plaque and the material of the case.

6. A toilet article comprising a cosmetic cake mounted upon an inert plaque, the plaque and attached cake contained within 30 a metallic casing, and a cushion pad disposed between the plaque and bottom of the case.

7. A toilet article comprising a cosmetic cake mounted upon an inert plaque, the 35 plaque and attached cake contained within a metallic casing, a cushion pad disposed between the plaque and bottom of the case, and a non-drying tacky cement substance attaching the pad to the plaque and to the 40 case.

In testimony whereof I have hereunto signed my name in the presence of two subscribing witnesses.

JESSE R. POWELL.
